United States Patent Office.

NORMAN W. WHEELER, OF BROOKLYN, NEW YORK.

Letters Patent No. 65,625, dated June 11, 1867.

IMPROVED WATER-ANCHOR.

The Schedule referred to in these Letters Patent and making part of the same.

TO ALL WHOM IT MAY CONCERN:

Be it known that I, NORMAN W. WHEELER, of the city of Brooklyn, county of Kings, and State of New York, have invented a new and useful Water-Anchor for sea-going vessels; and I hereby declare that the following is a full and exact description of the construction and operation thereof, reference being had to the accompanying drawings, with letters of reference marked thereon, making a part of this specification, in which—

Figure 1 represents a perspective view of the anchor when spread and as in use; and

Figure 2, a plan of the anchor partially folded—

Like letters of reference indicating the same parts in both figures.

Water-anchors or drags have been used heretofore for holding ships heads to the sea when they were disabled in their rigging or engines, and tended to lie in the trough of the sea, and in many cases have been merely spare spars or cases of merchandise attached to the fore part of the ship by ropes in such a way that the resistance afforded by the drag would tend to bring the ship into a safer position and diminish the drifting to leeward. Later, there have been in use upon a few ships water-anchors made in the form of umbrellas, with iron frames and heavy canvas covering attached thereto, which have usually performed their office well. One objection, however, may be made to this device, viz., the quantity of metal required for its fabrication causes it to sink too deeply below the surface when in use, thus making the angle of the hawser with the horizon too great.

The object of my invention is to provide a simple, light, and cheap water-anchor, which will be very efficient when in use, and capable of being folded into a small compass for stowage.

By reference to the drawings it will be seen that A A represent two cross-pieces, secured together by the bolt B in such a way that they may be opened or shut. E a parallelogram of canvas properly reinforced by ropes sewn thereto, and with the ropes f f g g attached to the corners of the canvas and also to the ring k. At D D the ropes g g pass through holes in the ends of one cross-piece, or may be secured thereto in any sufficient manner, while at c c are seen dead-eyes or thimbles let into the ends of the cross-piece in such a way that the ropes f f will render freely through them. When the cross-pieces a a are folded the ropes f f must render through the thimbles c c, as seen in fig. 2, so that a pull upon the ring k will only affect the ropes f f, and the ropes g g will remain slack until the cross-pieces are spread so as to coincide with the corners of the canvas.

Now if this anchor be attached to a ship which has motion through the water by a hawser made fast to the ring k, the weight of the anchor and the resistance of the water will cause the canvas to be spread out and offer a great resistance to the drifting of the ship to leeward. To the canvas E, which is cut so that it will be bellied out by the action of the water upon it, is attached by the rope m a weight, l, for the purpose of sinking the anchor to any depth required, the weight being detachable, and it may be added to or taken from, as occasion may require. Another action of this weight is to cause whichever side of the anchor is the lowest to assume a position in advance of the opposite side, and thus tend to force the anchor down and below the surface, and prevent the anchor skipping from crest to crest of the waves. To facilitate the handling of the anchor the rope i is attached to one of the cross-pieces at j, and led through the eye h in such a way that a pull upon the rope i will tend to draw the ends of the cross-pieces together and "spill" the canvas, so that if the rope i be fast to the ship, and left slack when the ship is riding to the water-anchor, it may easily be spilled and drawn on board; or the spilling line i may be attached to the ring k, sufficient slack being allowed, or even left to hang loose, and the anchor spilled after it has been hauled within reach of the men on board of the ship.

What I claim as my invention, and desire to secure by Letters Patent, is—

1. The water-anchor herein described, when the ropes f f are so arranged, in reference to the cross-pieces C D, as to expand the anchor by their tension, in the manner and for the purposes described.
2. In combination with the above, the spilling line, attached and operating substantially as and for the purposes described.
3. The combination of the weight l, canvas E, and cross-pieces A A, when arranged in the manner described.

NORMAN W. WHEELER.
